United States Patent Office.

THOMAS SMITH, OF BROOKLYN, NEW YORK.

Letters Patent No. 72,287, dated December 17, 1867.

IMPROVED TRUNK.

The Schedule referred to in these Letters Patent and making part of the same.

TO ALL WHOM IT MAY CONCERN:

Be it known that I, THOMAS SMITH, of Brooklyn, in the county of Kings, and State of New York, have invented a new and improved Trunk; and I do hereby declare that the following is a full, clear, and exact description thereof, which will enable others skilled in the art to make and use the same, reference being had to the accompanying drawings, forming part of this specification.

Figures 1 and 2 represent vertical transverse sections of my invention.

Similar letters of reference indicate corresponding parts.

This invention relates to a new extension-trunk, which is provided with an inside casing or tray, having hinged bottoms, which tray can be secured in an inverted position upon the cover of the trunk, extending the same, and forming a new compartment for packing goods. The bottom of the tray becomes, in this position, the cover of the trunk-extension.

A represents a trunk, made of wood or other suitable material, in any suitable manner, and of any suitable form or description. B is the tray, which, when inserted into the trunk, as in fig. 1, rests upon slats *a a*, arranged on the sides or ends of the trunk, for its support. The bottom, *b*, of the tray B, is hinged to the sides of the same by means of any suitable hinges; *e e* are ribs secured to the surface of the trunk-cover *d*. They are arranged so that when the tray B is placed in an inverted position upon the trunk-cover, as in fig. 2, they will fit against the inside walls of the tray, preventing the same from shifting on the cover. *e e* are staples fitted into the cover *d*, and *ff* are staples secured in the walls of the tray B. *gg* are straps fitted through the staples *e* and *f*, thereby securing the tray to the trunk-cover. The hinged bottom, *b*, of the tray forms, when the tray is secured upon the trunk, as in fig. 2, the cover of the tray, and the tray itself, forms an additional apartment upon the trunk, as shown. Whenever it is desired, the tray can be placed into the trunk, reducing the dimensions of the same.

The devices for fastening the tray to the trunk-cover may be varied at pleasure. The tray may be provided with a suitable lock for securely closing it, when arranged upon the trunk-cover. This invention will be very useful for travellers, as a trunk may be made more capacious, while the size can be reduced when it is to be stored away.

I claim as new, and desire to secure by Letters Patent—

1. The tray B of a trunk, when provided with a hinged bottom, *b*, substantially as and for the purpose herein shown and described.
2. So arranging a trunk, A, and its tray B, that the latter can be secured in an inverted position upon the cover of the trunk, by means of straps or otherwise, substantially as herein shown and described, so as to form a separate compartment upon the trunk, as set forth.

THOMAS SMITH.
